UNITED STATES PATENT OFFICE.

HARVEY W. SEIBER, OF CANAL DOVER, OHIO.

HORSESHOE.

1,145,273.

Specification of Letters Patent.

Patented July 6, 1915.

Application filed April 20, 1915. Serial No. 22,625.

To all whom it may concern:

Be it known that I, HARVEY W. SEIBER, a citizen of the United States, residing at Canal Dover, in the county of Tuscarawas and State of Ohio, have invented a new and useful Horseshoe, of which the following is a specification.

The device forming the subject matter of this application is a horseshoe, and the invention aims particularly, to improve the construction of the removable calks which are assembled with the shoe, and to provide novel means whereby the calks are held upon the shoe.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing: Figure 1 shows the invention in bottom plan; Fig. 2 is a section on the line 2—2 of Fig. 1; Fig. 3 is a section on the line 3—3 of Fig. 1; Fig. 4 is a section on the line 4—4 of Fig. 1; Fig. 5 is a section on the line 5—5 of Fig. 4; Fig. 6 is a side elevation of the heel of the shoe, the heel calk being detached; Fig. 7 is a top plan of the heel calk.

In the drawings there is shown a horseshoe 1 provided at its toe with a depending lug 2 which tapers as it extends downwardly as indicated at 3.

The invention comprises a reversible tubular toe calk 4, the interior of which is tapered, so that the toe calk may be wedged firmly onto the lug 2. At its ends, and in its interior, the calk 4 is equipped with longitudinal ribs 5 adapted to be received in longitudinal grooves 6 formed in the ends 45 of the lug 2. As shown at 7, the upper face of the calk 4 is spaced apart from the lower face of the shoe 1, so that the calk 4 may be wedged onto the lug 2 tightly and become more securely wedged thereon after a protracted period of use. As indicated at 8, the lower edge of the calk 4 is spaced below the lower end of the lug 2, and consequently, the entire periphery of the tubular calk 4 is made efficient to afford a ground gripping element. Owing to the manner in which the ribs 5 on the calk 4 coöperate with

the grooves 6 in the lug 2, the calk is firmly held on the lug. Further, the ribs serve to reinforce the calk. Again, it is to be observed that since the ribs 5 extend downwardly to the lower face of the calk 4, the inner edge of the calk is rendered discontinuous and interrupted, thereby enhancing the hold of the calk on the ground.

At its heels, the shoe 1 is equipped with tapered lugs 9 having longitudinal grooves 10 of the sort hereinbefore described. The reversible heel calks appear at 12 and are provided with tapered recesses 16 whereby the heel calks may be wedged onto the lug 9. The internal ribs of the heel calks 12 are shown at 11 and coöperate with the grooves 10 in the manner hereinbefore described. The upper face of each heel calk 12 is spaced apart from the lower face of the shoe 1, as shown at 14, and the lower end face of the lug 9 is spaced apart from the bottom of the recess 16, as shown at 15, to the end that the calk may be firmly wedged onto the lug. The working ends of the calks 12 may be shaped as desired. As shown at 17 they are of chisel form, but this feature of the invention is not insisted upon.

Generally considered, the present invention discloses a novel means whereby a calk 85 may be held on a lug of a horseshoe, the calk being reinforced and strengthened by those elements, towit, the ribs, which aid in holding the calk on the shoe lock.

The tubular toe calk 4 presents an unusually effective gripping surface and the ribs 5, as hereinbefore set forth, reinforce the calk, enhance the hold thereof on the ground and aid in retaining the calk on the shoe.

Having thus described the invention, what is claimed is:—

1. In a device of the class described, a shoe having a tapered lug provided in its side face with a longitudinal groove; and a calk 100 having a tapered recess in which the lug is wedged, the calk being provided in its interior with a longitudinally extended rib received in the groove and forming a reinforcement for the calk.

2. In a device of the class described, a shoe having a tapered lug provided in its side face with a longitudinal groove; and a tubular calk having a tapered recess in which the lug is wedged, the lower end of 110 the calk projecting below the lower end of the lug to afford an anti-slipping surface,

the calk being provided in its interior with
a longitudinal rib received in the groove,
the rib constituting a reinforcement for the
calk and serving to break the continuity of
5 the calk at the ground engaging end there-
of, thereby to enhance the hold of the calk
on the ground.

In testimony that I claim the foregoing as
my own, I have hereto affixed my signature
in the presence of two witnesses.

HARVEY W. SEIBER.
